UNITED STATES PATENT OFFICE.

WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

FLEXIBLE SET-BAR ACTION FOR PERFORATING-MACHINES.

1,311,566.

Specification of Letters Patent.

Patented July 29, 1919.

Application filed January 3, 1917. Serial No. 140,338.

To all whom it may concern:

Be it known that I, WILLIAM W. LASKER, a citizen of the United States, residing in Brooklyn, in the county of Kings and State 5 of New York, have invented certain new and useful Improvements in Flexible Set-Bar Actions for Perforating-Machines, of which the following is a specification.

This invention relates to accounting machines for statistical cards or the like in general, and more particularly to machines for perforating statistical cards and the like.

One of the main objects of the present 15 invention is to provide improved actuating mechanism in which in a single row of punches but one punch may be actuated at a time to the exclusion of the others; in which the actuation of a second punch in a 20 single row of punches will automatically release the punch previously actuated; and in which extension pins of comparatively thin stock may be used with great efficiency and accuracy.

25 These and other features, capabilities and advantages of the invention will appear from the subjoined detail description of one specific embodiment thereof, illustrated in the accompanying drawings, in which—

30 Figure 1 is a sectional view of a perforator equipped with the present improvements.

Fig. 2 is a detached sectional view of the connecting pin mechanism.

35 Fig. 3 is a fragmental end elevation of the mechanism illustrated in Fig. 2.

Figs. 4 and 5 are fragmental sectional views showing successive positions of a pin of the mechanism illustrated in Fig. 2.

40 In the embodiment illustrated there is provided a main frame M having secured at one end a card hopper C from which the cards to be perforated are fed to a position between the die plate 12 and the punch 45 guide plate 13 to coöperate with the punches 14 mounted in the perforations of the guide plate 13 with their heads 15 normally resting on the plate 16. From the plates 12 and 13 the cards are discharged into the receptacle 17 after having been perforated. The plates 12 and 13 are adapted to be vertically reciprocated so that the punches 14

50 may coöperate with the setting pins 18 to punch the cards in which operation the

punches 14 which have no setting pins 18 55 depressed in alinement with them will rise with the plates 12 and 13, while those punches 14 which are obstructed in their upward movement by depressed setting pins 18 will perforate the card. For each punch 60 14 there is provided a setting pin 18 disposed in alinement and directly above the same.

The setting pins 18 are preferably composed of flat stock and mounted and guided 65 in the alined openings of the plates 19, 20, 21, and 22. On the pins 18 there are formed collars 23 which are disposed below the plate 21, between which collars 23 and the plate 22 the springs 24 are strained, whereby the pins 18 are normally maintained in raised position. Along the body of the pins 18, preferably between the plates 20 and 21, the recesses 25 and 26 are provided which coöperate with the lower ends of the shutters 27 that are pivotally connected at their upper ends to the cross pieces 28 and 29, to which plates 19 and 20 are secured.

The recesses 25 and 26 of each row of pins 18 face in the same direction, a shutter being provided for each row of pins 18, so that a single shutter may coöperate with the recesses of all of the pins of that particular row. The lower ends 30 of the shutters 27 are preferably inclined inward 80 toward the pins 18 with which they coöperate. The shutters 27 are normally maintained in contact with the pins 18 by means of the springs 31 (Fig. 3) which are secured at their upper ends to the cross piece 90 29 and have their lower ends disposed against the lips 32 formed at the outer lower ends of the shutters 27.

For setting the pins 18 a transversely movable carriage 33 is provided on which the 95 key actuated plungers 34 are mounted. The carriage 33 is actuated across said pins 18 in a step by step movement so that its row of plungers 34 successively register with the rows of pins 18.

In the operation of the machine, with every actuation of a plunger 34 a pin 18 will be depressed in that row of pins 18 which is in registration with the plungers 34, which pin 18 upon being depressed will thrust the 105 shutter adacent thereto to one side until the bent portion 30 enters the upper recess 25 of such depressed pin 18. The portion 30 will

normally extend into the recesses 26 of the pins. Immediately after such pin 18 is depressed, and the plunger 34 is released, the carriage will be permitted to advance so that its plungers 34 will register with the next succeeding row of pins 18. This advance of the carriage 33 will continue until the entire record has been set for perforation whereupon the plates 12 and 13 will rise so that the punches 14 are raised and then those punches 14 which are obstructed by depressed pins 18 will perforate the card to reproduce a corresponding record while those punches 14 which are in alinement with the pins 18 that have not been depressed will rise with the card. Thereafter the shutters 27 will be rocked to one side and the pins 18 permitted to be raised by their springs 24.

20 The rocking of the shutters 27 is brought about by means of tripping keys 40 seated in transverse slots 41 in the rocker plate 35 mounted on a rocking shaft 42 provided with a downwardly extending arm 44 which is 25 rocked by means of a rod 45 engaged and reciprocated by a cam 46 carried on the shaft 48.

The tripping keys 40 are slidable toward and away from the shutters and are frictionally held in the slots 41. In order to lock the keys in inner or outer position there is provided a locking plate 54 carried on the outer face of said rocker plate 35 and adapted to engage the inner notch 56 or the outer 35 notch 57 of the keys 40. Only the keys 40 that are set in inner position rock the shutters 27. If it be desired not to release the pins 18 of any rows, the keys 40 of such rows are set in outer position.

40 In the operation of the foregoing, when the pins 18 were thus released the shutters 27 would sometimes fail to entirely free the edges of the recesses 25 and thus prevent the return of such depressed pins. To overcome this defect the shutters 27 are given a further rocking motion by the teats 36 formed on such pins 18 below the recesses 25, which teats 36 are well rounded to form cams whereby the pins 18 will easily ride 50 over the edges of the shutters 27. The teats 36 are uniquely formed on such pins 18 by stamping out or indenting the metal, in which case advantage is taken of the flat thin stock for the stamping operation, and in 55 turn a cheap and economic article produced. These teats 36 will rock the shutter more than enough to cause the shutter to clear the recess 25, of the previously depressed pin, whereupon the latter rises until the teat engages the shutter and by cam action pushes the shutter back, so that the first actuated pin will be automatically released to return to normal position whenever a second pin in such row is depressed.

60 65 It is obvious that various changes and

modifications may be made to the details of construction without departing from the general spirit of the invention.

I claim:

1. In a perforator having means for supporting a card, punches, setting pins for co-operating with said punches to perforate the cards, means for normally maintaining said pins in raised position, means for setting said setting pins, there being recesses in the sides of said pins, shutters for co-operating with said recesses to anchor said pins in depressed position when so set, and cams for facilitating the co-operation of said shutters with said setting pins. 70

2. In a perforator having means for supporting a card, punches, setting pins for co-operating with said punches to perforate the cards, means for normally maintaining said pins in raised position, means for setting said setting pins, there being recesses in the sides of said pins, shutters for co-operating with said recesses to anchor said pins in depressed position when so set, cams for facilitating the co-operation of said shutters with said setting pins, and means for actuating said shutters to permit said setting pins to be restored to normal position. 85

3. In a perforator having means for supporting a card, punches, setting pins for co-operating with said punches to perforate the cards, means for normally maintaining said pins in raised position, means for setting said setting pins, there being two recesses in the sides of said setting pins all facing 95 in the same direction, the setting pins being disposed in rows, a shutter for each row of setting pins to co-operate therewith to anchor the depressed pins in depressed position, and cams disposed below the first 100 recesses of said pins to facilitate the co-operation of such shutters with such setting pins. 105

4. In a perforator having means for supporting a card, punches, setting pins for co-operating with said punches to perforate the cards, means for normally maintaining said pins in raised position, means for setting said pins, there being two recesses in the sides of said setting pins all facing in 110 the same direction, the setting pins being disposed in rows, a shutter for each row of setting pins to co-operate therewith to anchor the depressed pins in depressed position, and a teat formed on each setting pin below its 115 upper recess for co-operating with a shutter to facilitate the co-operation of such shutter with such setting pin. 120

5. In a perforator having means for supporting a card, punches, setting pins for co-operating with said punches to perforate the cards, means for normally maintaining said pins in raised position, means for setting said setting pins, there being two recesses in the sides of said setting pins all 125 130

- facing in the same direction, the setting pins being disposed in rows, a shutter for each row of setting pins to coöperate therewith to anchor the depressed pins in depressed position, and an indentation made in each pin to press out the metal below its upper recess to form a teat to coöperate with a shutter to facilitate coöperation of such shutter with such setting pin.
- 5 6. In a perforator having means for supporting a card, punches, setting means composed of flat stock and coöoperating with said punches to perforate the cards, means for normally maintaining said pins in raised position, means for setting said setting pins, 15 there being two recesses in the sides of said setting pins, the setting pins being disposed in rows, a shutter for each row of setting pins to coöperate therewith to anchor the depressed pins in depressed position, and a 20 pressed out teat in each setting pin immediately below its upper recess for coöperating with a shutter to facilitate coöperation of such shutter with such setting pin.
